(57) **CLAIM**

The ornamental design for flow arm, as shown and described.

DESCRIPTION

FIG. 1 is a top outside rear perspective view of a flow arm front face according to my new design;

FIG. 2 is a top inside rear perspective view thereof;

FIG. 3 is an outside elevational view thereof;

FIG. 4 is a front elevational view thereof;

FIG. 5 is an inside elevational view thereof;

FIG. 6 is a rear elevational view thereof;

FIG. 7 is a top elevational view thereof; and,

FIG. 8 is a bottom elevational view thereof.

The broken lines shown in the drawing are for the purpose of illustrating environmental structure and form no part of the claimed design.
